UNITED STATES PATENT OFFICE.

WESLEY MACK HAMILTON, OF TAMPA, FLORIDA.

WATER-HEATING ATTACHMENT.

1,245,905.

Specification of Letters Patent.

Patented Nov. 6, 1917.

Application filed July 3, 1917. Serial No. 178,476.

To all whom it may concern:

Be it known that I, WESLEY M. HAMILTON, a citizen of the United States, residing at Tampa, in the county of Hillsborough 5 and State of Florida, have invented certain new and useful Improvements in Water-Heating Attachments, of which the following is a specification.

This invention relates to water heating 10 devices, particularly to water heaters associated with cook stoves, and has for its object the provision of a water heating attachment for gas ranges of the type having a plurality of horizontally disposed burners 15 at the top.

An important object is the provision of a water heating attachment comprising a plurality of coils so supported and positioned as not to interfere to the slightest degree 20 with cooking.

Another object is the provision of a water heater and storage tank associated therewith so arranged that a positive circulation of water will be maintained at all times, the 25 water inlet and outlet tubes being so positioned in different planes that there can be no backing up of heated water into the feed pipe.

Other objects and advantages such as simplicity and cheapness in the mounting of the coils, efficiency in operation, and the general improvement of the art, will be carefully brought out in the following description and 30 illustrated in the accompanying drawings, 35 in which;

Figure 1 is a vertical longitudinal sectional view through a gas stove equipped with my device,

Fig. 2 is a front view thereof, parts being 40 broken away and in section,

Fig. 3 is a top plan view, and

Fig. 4 is a detail view illustrating the mounting of the coils.

Referring more particularly to the drawings, the numeral 1 designates a gas range 45 having the usual oven 2 provided with burners 3 and 4, and the top plate 5 provided with the usual holes 6 below which are disposed the ordinary burners 7, the 50 holes being closable by the usual grids 8. This structure is old and forms no part of the present invention.

Mounted on a suitable bracket 9 at the rear of the stove is a water tank 10 of convenient size and shape and provided with 55 draw off cocks 11 and a suitable filling open-

ing. From the lower portion of the tank a pipe 12 extends down below the stove and then upwardly into the oven burner compartment where it is coiled about the burner 60 3 and then across and about the burner 4, after which the pipe extends upwardly through the top plate 5 and up to the top portion of the tank into which it empties.

Extending horizontally from the bottom 65 of the tank 10 is a pipe 13 which has its outer end 14 bent down and disposed within a feed opening in the top of a four way connection 15 which is disposed at the center of the top portion of the stove at the 70 maximum distance below the burners 7. From this connection extend four pipes 16, each of which is inclined upwardly to a point above the outer edge of a burner 7 and immediately below the grid 8, at which position 75 it is coiled twice upon itself to form a heating coil 17 having its convolutions in horizontal alinement. Each pipe 16 then extends horizontally below the top plate to a point adjacent the rear edge thereof at 80 which position each pipe leads upwardly along as at 18 and empties into the tank 10 at the upper end. In order that the assembled upper portions of these pipes may be hidden from view and also protected from 85 injury I provide a hood or shield 19 disposed upon the top plate, surrounding the upper portions 18 of the pipes and extending adjacent the tank 10.

In order that the coils 17 may be properly 90 supported in position, I provide a plurality of clips 20 at convenient intervals. Each of these clips comprises a short strip of metal disposed below one side of a coil and having its ends curved upward as at 21 to 95 prevent shifting, and held in place by a screw 22 extending downwardly from a strip of metal 23 extending part way over the opening 6 and secured to the top plate 5 by a small bolt 24.

In order that the heat from the burners may be confined and prevented from escaping uselessly into the air and being wasted, I provide the underside of the top plate 5 with a flange 25 which follows somewhat the 105 contours of the coils and which extends downwardly for an appreciable distance as shown.

In the operation of the device it will be seen that as the tank and pipes are primarily 110 full of water, lighting any of the burners will cause the coil thereabove to become

heated, consequently heating the water therein. As the water is heated it will pass upwardly through the pipes into the tank in accordance with the well-known principles 5 of physics. Of course, the more burners used, the quicker the water will be heated. It will be noted that the fourway connection supplying water to the coils is considerably below the coils, therefore insuring the prevention 10 of backing up of the heated water into the feed pipe, and thereby providing proper circulation. Furthermore, it will be observed that the initial convolution of each coil is nearest the burner, thereby causing 15 the coolest water to receive the most intense heat.

From the foregoing description and a study of the drawings it will be apparent that I have thus provided a simple attachment 20 for gas ranges whereby water may be rapidly heated without in any way interfering with culinary operations and with the minimum expenditure of fuel.

Having thus described my invention, I 25 claim:—

1. In combination with a gas stove having a top plate and a plurality of burners disposed therebelow; a tank, a feed pipe communicating with the bottom of said tank and disposed below said burners, a heating coil 30 disposed above each burner and connected

with said feed pipe, an outlet pipe connected with each coil and extending along the bottom of said top plate and upwardly through an opening therein and discharging into the upper portion of said tank, all of said outlet pipes being substantially parallel above said top plate, and a sleeve disposed upon said top plate, surrounding said outlet pipes and extending vertically to a point adjacent the entry of said outlet pipes into said tank. 35

2. In combination with a gas stove provided with a top plate and a plurality of burners spaced below said plate; a reservoir tank, a feed pipe communicating with the bottom of said tank and extending to a point between all of said burners and disposed in a plane considerably lower than the burners, and a plurality of pipes corresponding in number to the number of burners connected with said pipe and each extending upwardly in an inclined direction toward and above a burner and being coiled to form concentric convolutions with the primary convolution the innermost one, said coils each terminating in an outlet pipe extending along said top plate and upwardly therethrough and along said tank and communicating with the top portion of said tank. 40

In testimony whereof I hereto affix my 45 signature.

WESLEY MACK HAMILTON. 50
